UNITED STATES PATENT OFFICE

GEORGE B. GROSJEAN, OF SHREVEPORT, LOUISIANA

DRAIN PROTECTOR

Application filed April 17, 1930. Serial No. 445,147.

This invention relates to drain protectors and more particularly to devices adapted to be inserted into the drain proper.

The object of this invention is to provide a drain protector adapted to be inserted in a drain to prevent the entry of any foreign matter therein.

Another object of this invention is to so design the drain protector that the same may be handled as a unit, easily inserted in the drain and removed therefrom, simple in structure, efficient in use, and cheap to manufacture.

Other objects of this invention will become apparent as the description thereof given hereunder proceeds, reference being had to the accompanying drawing wherein:

Figure 1 is a plan view of the drain protector, and

Figure 2 is an elevational view thereof.

The drain protector is generically denoted by the reference numeral 10, and comprises a circular flange member 11, U-shaped in cross-section, the open end of which extends inwardly. Inserted in the flange member 11 and secured thereto in any desired manner is a wire screening 12, the mesh of which may be of any desired shape and size. Preferably the flange member 11 and wire screening 12, which essentially comprise the screen of the drain protector, are of such a size as to render the same more or less inflexible.

Extending above and below the plane of the screen of the drain protector is a plurality of U-shaped legs 13 equally spaced apart. Each of the legs 13 has a vertical portion 14 which extends through the screen 12 and is secured at its intermediate portion to the screen 12 by means of solder 15 or any other suitable securing means. It is to be understood, that the radial distance of each of the legs 13 from the center of the screen 12 are equal. The horizontal upper and lower portions 16 of the legs 13 extend radially inwardly and are permanently secured together by means of solder 17 or any other suitable fastening means.

The legs 13 as described above are rigidly secured to the screen 12 and serve to position the screen over the drain (not shown). The portion of the legs 13 which

extend above the screen 12 when the same is positioned over the drain serves to prevent the screen from becoming clogged up with solid foreign matter, thereby permitting water or fluid to flow the drain. The extended portion also serves as a means to insert or remove the whole device from a drain.

While a preferred embodiment of drain protector has been shown the same is susceptible of various changes within the scope of the appended claim.

Having thus described my invention, what I claim as new and desire to secure by Letters Patent is:

In a drain protector, a screen comprising an outer flange member and a wire screening attached to said flange member, and a plurality of legs secured to said screen and spaced from the center of said screen and from each other, each of said legs comprising a vertical portion and horizontal upper and lower end portions, the vertical portions being disposed through said screen and permanently secured thereto intermediate the ends thereof, whereby said legs extend above and below the plane of said screen, and means rigidly securing the horizontal upper and lower ends of said legs together.

In testimony whereof I affix my signature.

GEORGE B. GROSJEAN.
